US00D968988S

(12) **United States Design Patent** (10) **Patent No.:** **US D968,988 S**
(45) **Date of Patent:** **** Nov. 8, 2022**

(54) **GAS SENSOR**

(71) Applicant: **NEW COSMOS ELECTRIC CO., LTD.**, Osaka (JP)

(72) Inventor: **Ryo Kaimasu**, Osaka (JP)

(73) Assignee: **NEW COSMOS ELECTRIC CO., LTD.**, Osaka (JP)

(**) Term: **15 Years**

(21) Appl. No.: **35/512,274**

(22) Filed: **Jan. 28, 2021**

(80) **Hague Agreement Data**

Int. Filing Date: **Jan. 28, 2021**

Int. Reg. No.: **DM/212758**

Int. Reg. Date: **Jan. 28, 2021**

Int. Reg. Pub. Date: **Jul. 30, 2021**

(51) **LOC (13) Cl. 10-04**

(52) **U.S. Cl.**

USPC **D10/81**

(57) **CLAIM**

The ornamental design for gas sensor, as shown and described.

DESCRIPTION

1. Gas sensor
2. Gas sensor
- 1.1 : Perspective
- 1.2 : Front
- 1.3 : Back
- 1.4 : Left
- 1.5 : Right
- 1.6 : Top
- 1.7 : Bottom
- 1.8 : Cross sectional
- 2.1 : Perspective
- 2.2 : Front
- 2.3 : Back
- 2.4 : Left
- 2.5 : Right
- 2.6 : Top
- 2.7 : Bottom
- 2.8 : Cross sectional

In the reproductions, the broken lines illustrate unclaimed portions of the articles and form no part of the claimed designs; the dash-dot broken lines illustrate only the boundary between the claimed designs and the other portions of the articles; the portion of the gas detectors indicated by the oblique shading lines in the reproductions Nos. 1.3 to 1.5 and 1.7 of design No. 1 and 2.3 to 2.5 and 2.7 of the design No. 2 represents a translucent surface; the solid black surface shading in the reproductions Nos. 1.1 to 1.7 of design No. 1 represents the color black; the reproductions Nos. 1.8 and 2.8 partially illustrate cross-sectional views of the front panel, which are taken along the vertical line extending through the middle of the gas detectors in the front

(Continued)

views; hatched areas in the cross-sectional views represent cross-sections of the subject articles.

1 Claim, 16 Drawing Sheets
